24 Inventor
Harry T. Kusel,
By A. Miller Belfield Atty.

UNITED STATES PATENT OFFICE.

HARRY J. KUSEL, OF CHICAGO, ILLINOIS, ASSIGNOR TO STRONGHART COMPANY, OF CHICAGO, ILLINOIS, A CORPORATION OF ILLINOIS.

SMALL SAVINGS BANK.

Application filed June 29, 1921. Serial No. 431,173.

To all whom it may concern:

Be it known that I, HARRY J. KUSEL, a citizen of the United States, residing at Chicago, in the county of Cook and State of Illinois, have invented a certain new and useful Improvement in Small Savings Banks, of which the following is a full, clear, concise, and exact description, reference being had to the accompanying drawings, forming 10 a part of this specification.

My invention relates to small savings banks, and particularly to banks known as registering banks, for registering the amount of money in the bank.

15 One of the objects of the invention is to provide a simple and practical construction of bank, particularly adapted for use as a registering coin bank.

Another object of the invention is to arrange for the holding of a substantial number 20 of coins of different denominations.

Another object of the invention is to simplify the construction and thereby reduce the cost of manufacture.

25 Another object of the invention is to provide a simple, practical and easily operated locking device.

In the accompanying drawings Fig. 1 is a side elevation of a bank embodying my present invention;

Fig. 2 is a central vertical section of the same;

Figs. 3 and 4 are cross sections taken respectively on lines 3—3 and 4—4 in Fig. 2; 35 and

Fig. 5 is a view of a detail of construction.

Referring to the drawings, I show a bank 40 comprising a shell 1 forming the body of the bank, and a bottom 2 fitted and secured to the lower end of the shell 1. The shell 1 is preferably in circular form, as shown in Figs. 3 and 4, with a flat top 1^a, and an open lower end into which the bottom member 2 is fitted. The bottom 2 is preferably made 45 of a plate 2^a having its annular edge turned up to form an annular rim or flange 3 which fits snugly within the lower annular portion of the shell or casing 1. Another circular plate 4 is arranged above the plate 2^a and 50 within the annular rim or flange 3. This upper plate 4 has downwardly punched portions 5 forming feet 6 which rest upon the lower plate 2^a and are secured to the same as by rivets 7. Thus these two plates form a

hollow bottom with a space 8 between its upper and lower parts.

The shell or casing 1 is provided with a plurality of coin holding members 9, 10, 11 and 12. Preferably the members 9 and 11 are of a relatively large size and arranged 60 opposite one another and the holders 10 and 12 of a relatively small size and arranged opposite one another. The holder 9 is for quarters, the holder 10 for one cent pieces, the holder 11 for nickels, and the holder 12 6 for dimes. Thus provision is made for coins of four denominations. The shell or casing 1 is provided with slots 13, 14, 15 and 16 for the admission of coins to the holders 9, 10, 11 and 12, respectively. It is also provided 70 with series of apertures, as for example, 17—17 (Fig. 1), each series preferably having two rows of apertures staggered with reference to one another and extending upwardly and downwardly from top to bottom 75 of each holder, together with numerals indicating the value of the coins in each holder. Springs 18—18 are located at the respective slots 13, 14, 15 and 16, and preferably comprise clips secured to the top of the 80 shell or casing 1 and extending downwardly at an inclination in front of a coin slot, so as to permit the introduction of the coin to prevent the escape of the same. Preferably a plate 19 is secured to the top 1^a of the shell 85 1, as by rivets 20—20 and the spring clips 18 are secured to this plate 19 by means of rivets 21—21. Thus the coins may be introduced into the proper slots and will fall to the bottom of the holders 9, 10, 11 and 12 90 and lie upon the upper plate or false bottom 4 and as coins are added from time to time the value of the coins in each holder and therefore the value of all the coins in the bank may be determined.

95 As a locking arrangement for locking the casing 1 to the bottom 2, I show a rotary locking member 23 having a head 24 and also show the upper plate or false bottom 4 provided with an elongated aperture 25 adapted 100 to receive the head 24. Downwardly extending lugs or projections 26—26 are formed on the opposite sides of the aperture 25. Thus the elongated head 24 may be passed through the aperture 25 and then 105 turned part way around until it strikes the projections 26—26 when it is stopped and in this position it will engage the false bottom

4 and thereby lock the bottom to the shell or casing 1.

To permit turning of this locking member 23 the upper end of the same is preferably 5 provided with a square shaped portion or end 28 adapted to fit in the socket at the end of a key 29 whereby the turning of the key 29 a quarter turn will lock the bank and turning it a quarter turn in the opposite 10 direction will unlock the bank.

The rotary locking member 23 is preferably enclosed within a tubular member 30 (Fig. 3), having an enlarged upper extension 31 extending to the top 1^a of the shell 15 or casing and serving as a socket or chamber for the insertion of the key 29. The tubular member 30, 31, is preferably formed integral with the small coin holders 10 and 12, said coin holders and said tubular member being 20 made of two sheet metal pieces secured together by rivets 32—32, each of said pieces comprising substantially one-half of each of said coin holders and one-half of said tubular member, and also forming a web or partition 25 between said coin holders.

As a further structural feature, the rotary locking member 23 is preferably provided with a head 33 below its shank 28 and a split washer 34 is interposed between the 30 head 33 and the reduced tubular portion 30, so that the washer 34 will tend to spring the member 23 upwardly and thereby tend to hold it in locking engagement with the bottom floor 4 when the device is locked.

35 It will be understood that changes and modifications may be made without departing from the spirit of the invention.

What I claim is:

1. A small savings bank having a locking 40 device comprising a rotary member having an elongated head and a cooperating member having an elongated aperture adapted to receive said head, whereby a partial turn of said member will cause locking engagement.

2. A small savings bank having a locking device comprising a rotary member having an elongated head and a cooperating member having an elongated aperture adapted 50 to receive said head, whereby a partial turn of said member will cause locking engagement, and stops for limiting the rotary motion of said head.

3. A small savings bank having a locking 55 device comprising a rotary member having an elongated head and a cooperating member having an elongated aperture adapted to receive said head, whereby a partial turn of said member will cause locking engagement, said bank having a concealed chamber in which said head is confined.

4. A small savings bank comprising a circular shell or casing provided with a plurality of annularly arranged coin holders 60 fixedly secured to the top of said shell or

casing and a bottom detachably fitted into the lower end of said shell or casing.

5. A small savings bank comprising a circular shell or casing provided with a plurality of annularly arranged coin holders 70 fixedly secured to the top of said shell or casing and a bottom detachably fitted into the lower end of said shell or casing, said bottom being formed of upper and lower members with a space between and a locking device having a head arranged to fit in the space between said upper and lower members.

6. A small savings bank comprising a circular shell or casing provided with a plurality of annularly arranged coin holders 80 fixedly secured to the top of said shell or casing, and a bottom detachably fitted into the lower end of said shell or casing, said bottom being formed of upper and lower 85 members with a space between and a locking device having a head arranged to fit in the space between said upper and lower members, said locking device extending upwardly and having its upper end provided 90 with means for engaging a key.

7. A small savings bank comprising a shell or casing containing a plurality of coin holders secured to said shell or casing, a bottom fitted detachably into the lower open 95 end of the shell or casing, said bottom being composed of upper and lower members, with a space between them and a locking member carried by the shell or casing and having an engaging end adapted to pass through 100 the upper member of said bottom and into the space below the same so as to engage the under side of said member.

8. A small bank comprising a shell or casing having a closed top and open bottom, 105 coin holders secured to said shell or casing, a detachable bottom adapted to fit into the open end of the shell or casing, said bottom having upper and lower members with a space between them, a rotary locking member carried by the shell or casing and having an elongated head, said upper bottom member having an elongated aperture adapted 110 to receive said head, whereby the insertion of the head and the turning of the same will cause the locking of the bottom to the shell or casing.

9. A small bank comprising a shell or casing having a closed top and open bottom, 115 coin holders secured to said shell or casing, a detachable bottom adapted to fit into the open end of the shell or casing, said bottom having upper and lower members with a space between them, a rotary locking member carried by the shell or casing and having 120 an elongated head, said upper bottom member having an elongated aperture adapted to receive said head, whereby the insertion of the head and the turning of the same will cause the locking of the bottom to the shell 125 or casing.

or casing, said upper bottom member having its under side provided with projections forming stops.

10. A small bank comprising a shell or casing having a closed top and open bottom, coin holders secured to said shell or casing, a detachable bottom adapted to fit into the open end of the shell or casing, said bottom having upper and lower members with a space between them, a rotary locking member carried by the shell or casing and having an elongated head, said upper bottom member having an elongated aperture adapted to receive said head, whereby the insertion of the head and the turning of the same will cause the locking of the bottom to the shell or casing, said upper bottom member having its under side provided with projections forming stops, said locking member

20 being arranged centrally of the shell or casing and having its upper end arranged for engagement with the key.

11. A small bank comprising a shell or casing having a closed top and open bottom, coin holders secured to said shell or casing, a 25 detachable bottom adapted to fit into the open end of the shell or casing, said bottom having upper and lower members with a space between them, a rotary locking member carried by the shell or casing and having an 30 elongated head, said upper bottom member having an elongated aperture adapted to receive said head, whereby the insertion of the head and the turning of the same will cause the locking of the bottom to the shell or casing, said upper bottom member having its 35 under side provided with projections forming stops, and a split washer surrounding the rotary member and having a spring action tending to hold the locking device in 40 engagement.

In witness whereof, I hereunto subscribe my name this 20th day of May, A. D. 1921.

HARRY J. KUSEL.
